UNITED STATES PATENT OFFICE.

JAMES WILKINSON, OF BIRMINGHAM, ALABAMA.

PRESSURE-CONTROLLING MECHANISM FOR TURBINES.

No. 800,194.

Specification of Letters Patent.

Patented Sept. 26, 1905.

Application filed August 24, 1904. Serial No. 221,987.

To all whom it may concern:

Be it known that I, JAMES WILKINSON, a citizen of the United States, residing at Birmingham, in the county of Jefferson and State 5 of Alabama, have invented new and useful Improvements in Pressure-Controlling Mechanism for Turbines, of which the following is a specification.

My invention relates to an improvement in 10 pressure-controlling mechanism for elastic-fluid turbines.

In turbines where the motor-fluid pressure passes through an extended working passage in one or more casings, whether the turbine 15 be of the impact or expansion type, conditions may arise at intermediate points in the working passage, which from a point of economy or safety would demand the immediate reduction or complete stoppage of the supply 20 of motor fluid. This is true in connection with multicellular turbines, where the flow of the motor fluid is controlled by valves disposed at different points in the working passage, and particularly true where a speed- 25 governor is used to regulate the action of the supply or stage valves, or both, for the turbines will run for long periods even after pressure is cut off, and it follows that diminution of speed consequent to such disturbances 30 could not be relied upon to economically control the supply. Should any trouble arise with the condenser or exhaust or with any of the intermediate pressure-controller means, it would cause the motor fluid to bank 35 up in the working passages in a manner which would not only occasion a loss in the economical operation of the turbine, but would also subject the turbine shell or shells to an unnecessary and, according to some constructions, dangerous pressure strain. To meet 40 these conditions, it is my purpose to provide an automatic pressure-actuated controller means which will act independently of the normal governing or controlling means for 45 the supply of fluid to the turbine to reduce or cut off the supply of motor fluid when pressure begins to bank up at an intermediate point in the working passages. I preferably utilize a fluid-pressure controller 50 mechanism comprising a piston movable in a cylinder which is exposed at one end to the pressure existing at an intermediate point in the working passage and from which lead a plurality of conduits adapted to be successively opened to said pressure by the movement of a piston which is set to operate at

any desired pressure and to move in accordance with the excess of pressure. The admission of pressure to the conduits actuates means to close the supply-nozzles independently of their normal controller mechanism. 60

I have illustrated my invention as applied to a compound turbine comprising two separate shells or casings connected by a suitable conduit with which the controller-cylinder 65 is in communication, so that its piston is exposed to the pressure existing in the conduit.

My invention is capable of various applications, its broad principle consisting in the utilization of means sensitive to excessive intermediate or internal pressures to reduce the volume of motor-fluid supply or cut it off entirely independently of the controller mechanism, which latter may be operated by a speed-governor or by hand or in any desired 75 manner.

My invention comprises the details of construction and arrangement of parts hereinafter described and claimed, reference being had to the accompanying drawings, in which— 80

Figure 1 is a side elevation of a compound turbine provided with my invention applied between separate shells. Fig. 2 is a sectional view through the supply-head, partly broken away to show the nozzles and valve mechanism in elevation. Fig. 3 is a vertical sectional view through the automatic controller-chamber. 85

Similar reference numerals refer to the same parts throughout. 90

I have illustrated my present invention applied to a compound multiple-shell turbine, the high-pressure turbine 1 and the low-pressure turbine 2 being of any preferred type, such as shown and described in my Letters 95 Patent Nos. 761,865 and 761,866. The turbine 1 has an exhaust-head 3, which communicates through conduit 4 with the low-pressure turbine 2. These turbines drive a common shaft 5, the bearings 6 for which, together with the turbines, are mounted upon a common bed-plate 7. 100

Turbine 1 comprises a supply-head 8 and a plurality of diaphragms, which divide its interior into any desired number of stages, 105 within each of which rotates a bucket-wheel 9, carrying a row of bucket elements 10. The inner casing of the turbines are surrounded by annular shells 11, each of which is internally recessed to form an annular super-heating and supply chamber for the turbine, to which motor-fluid pressure is admitted 110

through port 12 in the side of the shell for turbine 1 and through a similar port 13 in the shell of turbine 2. The pressure from the supply-chamber is admitted to supply-valve 5 chambers 14, formed in head 8, through ports 15. The valves 16, which control the admission of fluid-pressure to the supply-nozzles, are operated by pistons 17, which move in the valve-chambers as cylinders, being exposed below to pressure admitted through ports 15. Screw-plugs 18 close the open end of these chambers, being recessed to provide a seat for springs 19, which engage the pistons, tending to move them downwardly to 15 close the valves. Thus far the construction and operation of my turbine responds to the disclosure in the patents aforesaid. A restricted passage 20 leads through each piston 17, for the purpose hereinafter described. 20 Controller-pressure from any suitable form of governing mechanism is admitted to each valve-chamber 14 through pipes 21, which communicate each with a passage 22, leading through an extension 23, integral with each 25 plug 18. This passage 22 leads to an auxiliary-valve chamber 24, which communicates by a port with the piston-cylinder 14, and within which is disposed a valve 25, operated by a stem 26, leading outwardly through a suitably- 30 packed opening in the extension 23 and connected at its outer end to a corrugated diaphragm 27, similar in construction to the diaphragm disclosed in my Letters Patent No. 761,865. These diaphragms are suitably 35 mounted in casings 28, being exposed below to the atmosphere and above to a pressure-tight chamber in each casing. The casings are mounted on supports 29. These diaphragms normally maintain the valves in their open position, so that controller fluid entering the valve-cylinders through pipes 21 will control the supply-valves in the usual manner, opening and closing them in accordance with the volume of pressure required and in the manner 40 described in the patent last referred to. It will be evident when I admit controller fluid, which is of equal pressure with the fluid-supply, above the pistons 17 they will be balanced between even pressures, when the 45 springs 19 will close the supply-valves. In like manner when valve 25 is seated and chambers 14 above the pistons are cut off from the fluid-pressure-governing mechanism, the pressure below the pistons will flow 50 through passages 20, and becoming balanced the valves will be closed by the springs. 55

The controller mechanism for the turbine-valves may be of any desired construction—such, for instance, as that shown in my Letters Patent aforesaid—and as it constitutes no part of my present invention it will not be described in detail herein. Its operation, however, is controlled by a speed-governor 30, mounted on a shaft 31 and driven by suitable 60 gearing 32 from the turbine-shaft, the shaft

31 being supported in a bearing 33, integral with bed-plate 7. The governor-collar 34 operates a bell-crank lever 35, pivotally mounted on a standard 36 and connected by a rod 37 to the controller device of the fluid-pressure-governing mechanism. (Not shown.) The pressure admitted by the governing mechanism under normal conditions flows in through suitable working passages, through the several compartments of turbine 1 to its exhaust-head, and thence through conduit 4 to the annular supply-chamber of turbine 2, from which it passes into the supply-nozzles therefor and through working passages to the exhaust-head 38 thereof, thence to the atmosphere of condenser. Valves may be used in the nozzle-passages between stages in turbines 1 or 2, or in both, any suitable controller mechanism being used to operate the stage-valves in correspondence with the supply-valves. When the supply of fluid admitted to turbine 1 is in excess of that being utilized by or flowing through turbine 2, either by reason of an oversupply or a restricted exhaust from turbine 2, due to trouble with the condenser or interruption of the flow between any of the stages in turbine 2, pressure will bank up in the conduit 4 and in the working passages. Such a condition will not only interfere with the proper action of the turbine, but will also materially affect its economy in operation, and it is my purpose to obviate this by providing a pressure-actuated controller mechanism which will act automatically and independently of the governing mechanism to reduce or shut off the supply of motor fluid. This comprises a casing 40, communicating at its lower end by pipe 41 with the conduit 4 and open at its upper end through port 42 to the exhaust or atmosphere. 90 A screw-plug 43 is in threaded engagement with the enlarged end 44 of the casing 40 and is recessed for the reception of a spiral spring 45, which at its other end bears against the head of piston 46. This piston has a stem 47, which projects through an opening in the plug 43, passing upwardly through the spiral spring 45. The lower face of the piston 46 is beveled to seat against a reduced beveled seat 48, into which pipe 41 enters. The piston and seat are beveled, to effect a definite and positive opening action of the piston when the pressure admitted through pipe 41 exceeds the pressure of the spring 45, which latter may be adjusted by screwing the plug 43 up or down in the head 44. I provide the plug with a handle 49 for the purpose of effecting this adjustment. From a side of casing 40 lead a plurality of ports 50, arranged equidistant and in vertical alignment and threaded at their outer ends. A pipe 51 is screwed into each of these ports and leads to one or more of the diaphragm-casings 28, entering chambers 52 therein above the diaphragms through ports 53. When pressure 100

105 110 115 120 125 130

is normal in the conduit 3, the spring 45 will maintain the piston 46 against its seat 48, when all of ports 50 will be exposed to the atmosphere, and accordingly each of the dia- 5 phragms 27 will be in its normal position and hold the auxiliary valves 25 open. Under this condition the governing mechanism will have full control of the turbine-valves. If, however, the pressure exceed the desired 10 point in the conduit, piston 46, which is exposed thereto, will be moved from its seat to a position where it will open a port 50 to the high pressure admitted through pipe 41. This pressure will flow through the pipe 51, com- 15 municating with the open port, to the chamber or chambers 52, with which it communi- cates, and will force the diaphragm or dia- phragms controlled thereby to a lowered po- 20 sition, where the auxiliary valve or valves 25 under their control will be closed. By thus closing one or more auxiliary valves the tur- 25 bine valve or valves controlled thereby will be withdrawn from the control of the gov- 30 erning mechanism and in the manner herein- before described will move to a closed po- 35 sition. As the pressure in the conduit 3 in- creases the pipe 51 will be successively opened to the high pressure and will successively withdraw the turbine-valves from the control 40 of the governing mechanism until they are all maintained closed and the supply of fluid en- tirely cut off. This controller mechanism will therefore coöperate with the governing mech- 45 anism in regulating the supply of motor fluid 50 and will increase the efficiency of the gov- ernor's control of multicellular turbines by making it sensitive to intermediate or final pressures throughout the working passages.

My invention is equally applicable to com- 40 pound turbines formed in a single casing, when the pipe 41 or a corresponding conduit may communicate with the pressure in or be- 45 tween any of stages or compartments succeed- ing the initial stage or compartment.

I have illustrated a preferred embodiment 45 of my invention; but I do not desire to limit myself thereto, it being my purpose to cover and protect by this application any character 50 of controller mechanism responsive to pres- sure conditions arising in a working passage for the motor fluid which coöperates with the governing or controller mechanism for the supply by closing the fluid-admission ports in- 55 dependently of the governing mechanism when intermediate pressure exceeds predeter- 60 mined points.

Having thus described my invention, what I claim as new, and desire to secure by Letters Patent, is—

1. In a turbine having a regulated supply of 60 motor fluid, the combination of emergency means controlled by abnormal conditions of pressure in the turbine to reduce or stop the motor-fluid supply to the turbine, with a speed- 65 responsive device, and means under its con-

trol to automatically regulate the supply of motor fluid under normal conditions.

2. In a turbine, the combination of a speed- 70 responsive device, means controlled thereby for regulating the supply of motor fluid to the turbine, with means controlled by the pres- 75 sure of the motor fluid during its active serv- ice in the turbine or turbines which act to vary the volume of the fluid-supply independently of said speed-responsive device, as and for the purposes described.

3. In a turbine having a valve-controlled 80 working passage, the combination of governor- controlled means to regulate the admission of fluid-pressure thereto in accordance with the 85 load on the turbine, with means, controlled by abnormal pressures in said passage, which are adapted to assume control of the admis- 90 sion of fluid-pressure independently of said first-mentioned means.

4. The combination with a turbine, of a controller means sensitive to speed or load, and a controller means sensitive to internal pressure conditions, both of which coöperate under determined conditions to regulate the sup- 95

ply of motor fluid.

5. In a turbine, the combination of gov- 95 ernor-controlled means to regulate the supply of motor fluid, with automatic pressure-actu- ated means to cause a reduction in the motor- 100 fluid supply when for any reason the pressure in the turbine exceeds a predetermined amount.

6. In a turbine having a plurality of fluid- 100 admission passages, a controller means to vary the volume of the fluid-supply in accordance with the load, and means operated by exces- 105 sive internal pressure to cut said passages suc- cessively out of service.

7. In a multiple-nozzle turbine, valves for 105 said nozzles, a governing means to operate said valves, and means to cut said valves out from the control of said governing mechanism and close all or part of them, when the pressure in the turbine banks up or becomes excessive 110 from any conditions.

8. In a turbine, a working passage for the 115 motor fluid, a supply-valve for said passage, means responsive to load conditions which operate said valve, a conduit leading from an intermediate point in said working passage to conduct fluid-pressure therefrom to effect the closing of said valve, and a valve in said conduit which is opened by abnormal pressures in said working passage to admit fluid-pres- 120

ure to close said supply-valve, substantially as described.

9. In a compound multicellular turbine, a 125 plurality of supply-nozzles, fluid-actuated valves therefor, a controller mechanism for said valves, and a controller-chamber communi- cating with the interior of the turbine and having a plurality of conduits leading there- 130 from, means controlled by the pressure in said conduit to cause said valves to open or close

independently of said governing mechanism, and a valve in said chamber which maintains said conduits closed until exposed to predetermined pressure when it successively admits said pressure to said conduits to close the valve or valves under their control.

10. In a multiple-nozzle turbine having fluid-actuated valves, and a governing mechanism therefor, an automatic pressure-controlling mechanism comprising a chamber communicating at one end with the interior of the turbine and at the other with a low pressure, a spring-pressed piston-valve therein held to its seat against any but excessive pressures in the turbine, and a plurality of conduits leading from said cylinder to conduct fluid-pressure therefrom to close said valves.
11. In a compound multicellular turbine having a plurality of working passages, valve-controlled nozzles admitting pressure to said passages, and means to control the operation of said valves comprising a fluid-pressure-governing mechanism and an automatic pressure-controlled mechanism which interrupts the control of said governing mechanism when the pressures in said working passages become abnormal, said controller mechanism acting subject to said abnormal pressures to close one or all of said nozzles.
12. In a plurality of turbines operating in series, a conduit connecting them, a chamber communicating with said conduit and with means to vary the supply of motor fluid to the turbines, a valve in said chamber, and adjustable spring means to hold said valve to its seat until a predetermined pressure exists in said conduit, when said valve is unseated thereby and admits pressure to said first-mentioned means to cause a reduction in the volume of fluid-pressure supply for the turbines.

13. In a turbine, a nozzle supply-passage, a piston-actuated valve therefor, a cylinder

for said piston exposed to said supply-pressure below and a governed pressure above, spring means coöoperating with one of said pressures to cause said valve to close, and means controlled by the interior pressure of the turbine to interrupt the admission of governed pressure above said piston, for the purposes described.

14. In a turbine, a nozzle, a valve therefor, a fluid-motor for actuating said valve comprising a cylinder and piston, means to admit a governed pressure to said cylinder to control the operation of said piston, and valve means to interrupt the admission of said pressure to the cylinders, said valve means being actuated by pressure under the control of an interior pressure-actuated safety device, and said pistons being adapted to move to a valve-closed position when said governed pressure is interrupted.

15. In an elastic-fluid turbine, the combination of a plurality of wheel-compartments, conduits connecting said compartments, and rotatable buckets against which said conduits discharge motor fluid, valve means to control the supply of motor fluid to the first wheel-compartment, means to control the operation of said valve means, and means exposed to the motor-fluid pressure in one of said conduits between said wheel-compartments, said latter means operating responsive to predetermined conditions of said pressure of said motor fluid and being adapted to reduce or cut off the supply of motor fluid to said first wheel-compartment.

In testimony whereof I have hereunto set my hand in presence of two subscribing witnesses.

JAMES WILKINSON.
